UNITED STATES PATENT OFFICE

2,435,559

TRIMMING BOARD

Frank M. Lund, Chicago, Ill., assignor of fifty
per cent to Harvey M. Pushker, Chicago, Ill.

Application August 24, 1945, Serial No. 612,433

6 Claims. (Cl. 164—44)

1

My invention relates to trimming boards and, more in particular, to a trimming board having an improved paper stop of the general type shown in my prior Patents Nos. 2,185,985 and 2,327,000.

A preferred embodiment of the invention is shown in the accompanying drawing wherein—

Fig. 1 is a fragmentary perspective view of a trimming board constructed in accordance with the features of my invention;

Fig. 2 is a fragmentary enlarged transverse sectional view taken on the line 2—2 of Fig. 1; and

Fig. 3 is a fragmentary transverse sectional view taken on the line 3—3 of Fig. 2.

Looking now to the drawings, the trimming board of my invention utilizes a base 10, preferably made of wood or the like, having cross pieces 11 and with the base preferably provided with suitable indicating lines 12 on the face thereof. A plate 13, providing a cutting edge, is secured along one side of the rectangular base by screws 14 and a cutting knife 16 is suitably pivoted to the base so as to cooperate with the cutting edge for the purpose of trimming photographs or the like, with the sides straight and square to each other.

In accordance with the general features of my invention, I provide a paper guide 17 along one side of the rectangular base 10 against which the paper may be held in cutting operation and provide a paper stop 18 positioned to gauge the depth of the cut. I provide a pair of ledges at opposite sides of the base with a clamping mechanism so constructed and arranged that the paper stop 18, and a part of the clamping mechanism associated therewith, are tensioned between the two ledges and the paper stop forced tightly against the upper surface of the rectangular base.

In the specific form of invention shown, the paper guide 17 has a general Z shape and a portion thereof 17' extends downwardly at a slight angle. The lower portion of the Z comprising the paper guide 17 is set in a slightly recessed portion of the top face of the base member and is held in position by screws 19. The opposite edge of the rectangular base 10 is tapered, as indicated at 21, and a hook-like portion 22, which preferably may comprise a part of the paper stop 18, hooks under the ledge comprising the portion 21. The clamping mechanism comprises a clamp spring 23 secured to an intermediate portion of the stop 18 by suitable means such as screws 24, the clamp spring extending toward

2

the opposite end of the paper stop and upwardly at an angle and having a hook-like portion 26, engaging under the ledge 17'. A pair of ears 27, integral with the clamp spring 23, project upwardly and a clamp 28 has ears 29 disposed within the ears 27, a pin 31 extending between the two sets of ears to hinge the clamp spring 23 and clamp 28 together. The clamp 28 has a tail piece 32 engaging in an opening 33 in the manner shown particularly in Fig. 2.

When using the trimming board, the clamp is raised to the position shown in dotted lines in Fig. 2 and the paper stop 18 is readily moved to a desired position, with respect to the cutting edge. The paper stop and clamping mechanism can be entirely removed from the board by merely sliding it beyond one end thereof. When the stop has been placed at the desired position, however, the clamp is lowered to the position shown in full lines. The paper stop is forced down tightly against the top surface of the base 10 by the tail piece 32 and, at the same time, the hook-like portion 26 is forced slightly upwardly and this causes the paper guide to move slightly to the right, looking at Fig. 2. The mechanism is thereby drawn tightly between the two ledges. This drawing action not only results from a virtual shortening of the two end supports but also a clamping action due to the raising of the portion 26 along the slanting edge of the ledge 17'.

I have described my invention in detail but the scope thereof is defined in the appended claims.

35 What I claim as new and desire to protect by Letters Patent of the United States is:

1. In a trimming board, a rectangular base having a cutting edge along one side thereof, means providing a pair of parallel ledges at right angles to said cutting edge, a paper stop disposed parallel to said cutting edge, and means including a pivoted clamp mechanism between ends of the said paper stop for tensioning said paper stop between said ledges and holding it tightly against said base.

2. In a trimming board, a rectangular base having a cutting edge along one side thereof, a paper guide having a ledge along one side of said base at right angles to said cutting edge, means providing a ledge at a side opposite to said paper guide, a paper stop disposed parallel to said cutting edge, and means including a pivoted clamp mechanism between ends of the said paper stop for tensioning said paper stop between said ledges and holding it tightly against said base,

3. In a trimming board, a rectangular base having a cutting edge along one side thereof, a paper guide along a side contiguous to said edge, said paper guide shaped to form a ledge, means providing a ledge at that side of the base opposite to said paper guide, a paper stop having a hook portion engaging said second ledge, a clamping member having a hook portion engaging said first ledge, and means including said clamping member and a second clamping member pivoted to the first mentioned clamping member to draw said hook portions together and fix the position of the paper stop on said base.

4. In a trimming board, a rectangular base having a cutting edge along one side thereof, a paper guide along a side contiguous to said edge, said paper guide shaped to form a ledge, means providing a ledge at that side of the base opposite to said paper guide, a paper stop having a hook portion engaging said second ledge, a clamping member having a hook portion engaging said first ledge, a clamp spring having one end secured to an intermediate portion of the paper stop, said clamping member having a tail piece extending into an aperture in said clamp spring and a pivot connection between said clamping member and clamp spring, so constructed and arranged that said tail piece connection to said clamp spring when said clamping member is rotated to clamping position will cause shortening of the distance between said hook portions and fix the position of said paper stop on said base.

5. In a trimming board a rectangular base having a cutting edge along one side thereof, a paper guide along one side perpendicular to said cutting edge, said paper guide being of general Z shape and having an upstanding portion de-

fining a ledge running perpendicular to said cutting edge, said base having its opposite side shaped to provide a ledge below its top surface, a paper stop having a downwardly extending hook portion engaging said second ledge, a clamp spring having one end secured to an intermediate portion of said paper stop and extending slightly upwardly at an angle beneath said paper guide, and a clamp pivoted to said clamp spring 10 and having a tail piece extending through an aperture therein, said clamp and clamp spring arrangement being so constructed and arranged that said clamp simultaneously depresses said paper stop against said base and raises the said clamp spring against the ledge to thereby hold the said stop in position.

6. In a trimming board, a rectangular base having a cutting edge along one side thereof, means providing a pair of parallel ledges at right angles to said cutting edge, a paper stop having a hook-like portion engaging under one such ledge, a clamp member having a hook-like portion engaging under the other such ledge, and a pivoted clamp between said paper stop and clamp member to force the paper stop against the base and tension said hook-like portion between the said parallel ledges.
